COLLAR

Richard Spanney, Mount Lawley, Western Australia, Australia

Application May 22, 1940, Serial No. 336,651
In Australia July 24, 1939

3 Claims. (Cl. 2-132)

This invention relates to improvements in collars, more specifically to improvements in soft collars of the turn-down type.

It is well known that such type of collar is not normally satisfactory because it becomes creased and wrinkled, which seriously detracts from its appearance. Many arrangements have been devised to overcome the foregoing disadvantage, but it is not considered that any of them are entirely satisfactory. They are unsatisfactory insofar as creasing and wrinkling are not sufficiently prevented or else the cost of the collars becomes unduly high.

The object of the present invention is to overcome the disadvantages above referred to, and to provide slipping means by the use of which creasing and wrinkling will be prevented so that a satisfactory appearance of a collar may be maintained, and whereby cheap materials can be used, thereby reducing the cost.

The invention in its broadest form comprises the use of a flexible stiffening member comprising a base firmly but removably held in or against the inner leaf or fold of the collar and having an extension that is adapted to be held to the peak either by being supported inside a peak pocket or else by some equivalent form of attachment. There are, however, several forms of the invention disclosed which will be understood by reference to the accompanying drawing, in which:

Fig. 1 is a view of one end of an outfolded collar, showing stiffening means embodying one form of the invention applied thereto;

Fig. 2 is a vertical section through the end of the collar in folded condition and with the stiffening means as disposed when the collar is worn;

Fig. 3 is a view similar to Fig. 1, showing another form of the stiffening means;

Fig. 4 is a section on line 4-4 of Fig. 3;

Fig. 5 is a section similar to Fig. 2 of the structure shown in Figs. 3 and 4;

Fig. 6 is an inner elevational view of an outspread collar embodying still another form of the stiffening means; and

Fig. 7 is a longitudinal section on line 7-7 of Fig. 6.

Fig. 8 is a section on line 8-8 of Fig. 6.

Referring now to Figs. 1 and 2, showing the structure at one end of the collar which is duplicated at the other end of the collar, the inner leaf or fold of the collar is referenced 10, whilst the outer fold is indicated by the reference numeral 11. The peak at each end of the outer fold is indicated by the numeral 12. At each end of the collar there is a flexible

stiffening member 13 comprising two unitary parts, a base 13^a and an extension 13^b. The peak is formed with a pocket 14 in which the extension 13^b of the flexible stiffening member 13 is slipped when the parts of the collar are in actual wearing position. The part 13^a of the member 13 stiffens the end of the fold 10 and the effect of the arrangement described is to confer a substantial degree of stiffness to the collar at the ends of the fold 10 and at the peaks of the fold 11 when the stiffening members are applied to the fold 10 and fitted in the pockets of fold 11 for use. The stiffening member is connected to the inner fold 10 of the collar by a bolt 15 so that the base 13^a of such flexible member is held in stiffening relation to the fold 10 at all times, while the stiffening member may be swung on said bolt 15 as a pivot, parallel with the fold 10, to engage the extension 13^b with or disengage it from the pocket of the peak.

By this means the ends of the fold 10 and peaks of the fold 11 will be stiffened and prevented from creasing or wrinkling when the collar is in use. This form of the invention will obviously be applicable to any existing collar, that is to say, the collar will not have to be specially manufactured, but each stiffening member can be connected to it by means of a bolt 15.

The form of the invention illustrated in Figs. 3, 4 and 5 differs from the construction shown in Figs. 1, 2 and 3 in this respect, that the stiffening member is comprised of two separate parts, namely, the base part 17 which is held against or in the inner fold 10 of the collar and the extension 18 which is pivoted thereto by an eyelet or bolt 15^a passing through a slot 19 therein and which is also capable of some relative movement by movement of its fulcrum in the slot 19. It should be noted that in effect the stiffening members 17 and 18 together are equivalent to the parts of the stiffening member 13 previously referred to. It should further be noted that, although those two parts of the stiffening member are capable of relative movement such relative movement is in the same plane. Outside of such plane these two parts are only capable of relative movement by a temporary distortion due to their flexibility. In consequence the extension 18 when connected to the peak of the outer leaf serves to hold the latter against creasing. The advantage of the slot is that the extension can be adjusted. If there is any shrinkage in the collar then the extension can be pushed in so that it firmly takes up a position in the pocket 14.

The form of the invention illustrated in Figs. 6, 7 and 8 differs only from that shown in Figs. 3, 4 and 5 in this respect, that the portion of the stiffening member held in the inner leaf or fold of the collar, that is, the base part 17^a of the stiffening member, is extended so as to confer rigidity over a considerable area of such fold. As shown, it extends the full length of the inner fold 10. The construction otherwise is the same as that shown in Figs. 3, 4 and 5.

It is to be noted that in each form of the invention there is a flexible stiffening member comprising a base which is firmly held in and against or in juxtaposition to the inner leaf or fold of the collar and an extension that engages and holds the peak of the collar to give the desired appearance referred to.

With a full length and depth stiffening member inserted into the inner leaf, and the peak stiffening members tightly adjusted, the softest and limppest collars can be stretched to suggest a starch finished surface.

I claim:

1. A stiffener for soft turn down collars comprising a base member capable of being retained between the folds of the soft collar, a flexible member, means for pivotally connecting one end of said flexible member to said base member whereby the same may rotate in a plane parallel with said base member, means whereby said flexible member may be longitudinally adjusted in the same plane in which it may rotate with re-

spect to said base member, and a relatively long extension formed with the opposite end of said flexible member.

2. A soft, unstarched or semi-stiff collar having an outer fold and an inner fold, pockets formed within the peaks of the outer fold, a stiffener comprising a base member arranged between and extending longitudinally throughout the inner and outer folds of the collar, flexible members each having one end seated within one of the pockets formed within the peaks of the outer fold of the collar, and a slot and pin connection between the opposite ends of said flexible members and the opposite ends of said base member, whereby said flexible members may be rotated upon said base member and be adjusted longitudinally with respect to the peaks of the outer fold of the collar.

3. A soft, unstarched or semi-stiff collar having an outer fold and an inner fold, pockets formed within the peaks of the outer fold, flexible members each comprising a base for stiffening the inner fold and an extension part adapted to fit within a pocket of one of the peaks to stiffen the same, and a connecting element between each flexible member and the inner fold fastening said member to said fold and also forming a pivot adapting the extension part to be swung parallel with the fold into and out of engagement with the pocket.

RICHARD SPANNEY.
